UNITED STATES PATENT OFFICE.

ALEXANDER GEORGIEVITCH ROTINOFF, OF LONDON, ENGLAND.

CONSTRUCTION OF FERROCONCRETE PILES IN SITU.

1,347,973.

Specification of Letters Patent. Patented July 27, 1920.

Application filed November 13, 1919. Serial No. 337,877.

To all whom it may concern:

Be it known that I, ALEXANDER GEORGIEVITCH ROTINOFF, an Armenian Russian subject, residing at London, England, have 5 invented certain new and useful Improvements in Construction of Ferroconcrete Piles *in situ*, of which the following is a specification.

This invention relates to the construction 10 of ferro-concrete piles and the like *in situ* and comprises a method of filling up and ramming the concrete in the holes, and improved apparatus therefor.

Although the invention will be described 15 as applied to the manufacture of piles, it will be understood that a concrete column could in a similar manner be built up in a form or mold, and where reference is made herein to piles, it is to be understood to include also columns or the like.

Practice has shown that many accidents 20 that have occurred to piling of the above described type, have been due to the bad execution of the work, the concrete being irregularly rammed and cavities having actually been left in important parts of the pile.

Such difficulties are attributable not only 25 to the unsatisfactory ramming as aforesaid but also, when a tube or mold is employed which is subsequently withdrawn, to the detrimental action of the withdrawal of the tube or mold during the issue of the concrete therefrom into the hole.

30 The existing methods of ramming and the lifting of the concrete with the tube during withdrawal of the latter are unsatisfactory. They are unreliable and make the work hazardous and uncertain. They do not give 35 any possibility of verifying the quality of the work done at the bottom of the tube, or of insuring the uniform compactness of the concrete.

The object of this invention is to give 40 absolute security that the concrete shall be uniformly rammed or pressed from the bottom to the top of the pile.

An important feature of the present invention is that the withdrawing of the tube 45 and its appurtenances is automatically effected by reason of a reaction set up against the concrete itself when but not until it is sufficiently compacted, thus converting what has heretofore been the detrimental action 50 of removing the tube into an action indi-

cating that the concrete has been rammed to the desired degree.

A further feature of the invention is that uniform density of the concrete in the pile is insured by sending the concrete down in 60 uninterrupted flow in a layer of screw-shaped helical form having the same thickness (and this is a limited thickness) from the bottom to the top of the pile.

The invention comprises broadly a method 65 of making a concrete pile or column which consists in depositing the concrete in a screw-shaped spiral layer, preferably a continuous layer, and compacting the deposited concrete, as for example by a steady pressure or by tamping.

One form of apparatus for carrying out the present invention comprises a loaded feed-worm for the concrete whose diameter is approximately equal to that of the bore-hole or form, and means to rotate it so that it gradually forces itself out of the bore-hole or cavity by its reaction with the surface of the concrete as the latter becomes compacted by the worm. 75

Thus the apparatus comprises feeding-means to deposit a screw-shaped spiral layer of concrete commencing at the lower end of the bore-hole or form, and means to compact the concrete as it is laid. 80

Preferably there is provided a reservoir-tube containing the feed-worm and operatively connected with it, with or without a lost-motion device in connection with the said tube and worm, and with or without a hammering device operative to transmit blows through the feed-worm to the laid concrete to compact it. 90

The foregoing and other features of the invention will be more clearly understood 95 from the following description of one preferred form of the invention read in conjunction with the accompanying drawings, in which—

Figure 1 illustrates, mainly diagrammatically, the apparatus at the commencement of the filling operation, the lower part of the figure being partly in section;

Fig. 2 is a section on the line 2—2 of Fig. 1 with the bore-hole casing and reinforcing 105 frame not shown, and

Fig. 3 is a diagrammatic illustration of the apparatus and its carriage.

Like letters indicate like parts throughout the drawings.

The apparatus comprises a reservoir-tube 1 at the bottom of which is a screw-shaped ram 10. The latter is centrally inserted in the reservoir-tube 1 at its bottom and is connected by means of a spindle 11 with a worm-wheel 12 at the top of the tube. The worm-wheel 12 is feathered on to the spindle 11 so that the latter may move vertically in relation to the worm-wheel but both will 10 rotate together.

The worm-wheel 12 meshes with a worm 13 carried in brackets 2 which are slidably engaged with an upright 20 of the supporting frame. At or near its upper end the 15 spindle is supported in a bearing 16 and at its lower end in a bearing 17 both secured to the reservoir-tube 1. Shoulders 18 and 19 respectively formed on the spindle limit the extent of the downward or upward motion 20 of the latter relatively to the reservoir-tube 1. That is to say, these shoulders limit the degree of lost-motion permissible between these two parts. The worm 13 is driven by an engine 3 carried on the reservoir-tube 1. 25 The latter is formed with a lip 4 to facilitate charging of the concrete into the reservoir-tube.

There is a hammering device at the top of the tube which consists of a non-rotating monkey 5 capable of sliding up and down and preferably guided in this sliding movement by means of bolts 6 whose inner ends are received in slots provided for their reception in the monkey 5. The bolts 6 are carried in a frame 7 which is secured to the reservoir-tube 1 as shown in Figs. 1 and 2, and which has at its upper end an eye-bolt 8 by which the reservoir-tube and its parts may be conveniently raised or lowered. The 35 frame 7 also has brackets 9 providing bearing-surfaces for the worm-wheel 12.

At the upper end of the spindle 11 is secured a ratchet-toothed member 14 adapted to engage a correspondingly-toothed ratchet-member 15 secured in the lower end of the monkey 5. As the worm-wheel 12 and the spindle 11 are rotated, the ratchet-member 14 will be rotated with the spindle and as the monkey is restrained from rotation, the 45 teeth or cam-surfaces of the member 14 cooperating with those of the member 15 will raise the monkey until the high part of the tooth of member 14 passes the corresponding portion of the tooth on the member 15, 50 when the monkey will drop suddenly. Thus, an intermittent hammering operation is produced, repeated at frequent intervals in accordance with the speed of rotation of the spindle 11.

60 In Fig. 1 a bore-hole casing (or forming-tube as it is called) is shown at 30 connected with the chains 31 by which it may be lowered into the bore-hole and by which it may be removed therefrom. Within the casing 65 30 is a reinforcing framework 40 and within

this framework the reservoir-tube 1 is situated. In Fig. 2, however, the casing 30 and the framework 40 are not shown although it will be understood that both may be present.

70 Fig. 3 diagrammatically illustrates the means by which the reservoir-tube 1 and its associated parts are carried. A traveling tower, indicated generally by the reference numeral 21, is arranged to travel on rails 22 75 so that it may be moved from place to place and on the platform at the base of the tower is supported a boiler 23 and a winding engine 24 by means of which the reservoir-tube and its parts are raised and lowered. 80 The vertical member of the tower 21 is formed with ribs 20 previously referred to in connection with Fig. 2, which engage within grooves in the bracket 2 to afford the necessary sliding connection between the 85 bracket and the tower.

In operation, the bore-hole casing 30, which would have been gradually advanced into the bore-hole as the latter was driven, may either be withdrawn before, or may remain in place during, the insertion of the reservoir-tube 1. In either case the reservoir-tube 1, and the reinforcing framework 40 placed outside it, are lowered into the hole, preferably after the reservoir-tube has 90 been filled with concrete. If the casing 30 remains in position when the reservoir tube is inserted, it may be withdrawn gradually as the work proceeds by means independent of the ramming mechanism. 95

100 The engine 3 is then set in motion and operates to rotate the spindle 11. Once in motion the screw-shaped ram 10, begins to rotate in the "unscrewing" direction, sending the concrete down out of the tube in an uninterrupted spiral layer; meantime the repeated blows of the monkey 5 give vertical vibrations to the ram, compressing the concrete. The ever-increasing compactness of the concrete under the ram reacts on the 110 latter and causes it to lift the tube gradually out of the hole.

115 Preferably additional screws or propellers 100 are provided on the spindle 11 to aid in feeding the concrete down through the reservoir-tube 1.

120 Instead of using the helical ram central in the tube, the latter may itself form a ram fitted with internal helical guide-vanes for the concrete. This may be hammered by a suitable hammering device so that the concrete issues in a spiral which, when compacted, reacts on and raises the tube; or alternatively, instead of hammering, the tube could be sufficiently weighted so that the 125 helical guide-vane constitutes the loaded feed-worm hereinbefore referred to which, by the steady pressure of its own weight, is sufficient to compact the concrete.

130 It will be understood that the bore-holes

can be filled without the use of the reinforcing framework such as 40, and obviously the bore-hole in the earth as illustrated, could be replaced by a mold on the surface.

5 The lost-motion which is permitted between the spindle 11 and the worm-wheel 12 enables the spindle to move axially in relation to the tube but when the spindle rises through more than the extent of the lost-motion it will take the tube up with it.

One particular form of apparatus for carrying the invention into effect has been described in detail but it will be obvious that the invention is not limited to the particular 15 construction of the parts as illustrated, as these may be varied as may be found convenient provided that the spirit and scope of the invention, as defined by the claims, is not departed from.

20 A portion of the weight of the reservoir-tube 1 and its contents can if desired, be counterbalanced by any convenient means, say for example by a wire 2^a led from the brackets 2 up over a pulley 2^b on the tower 25 21 and thence down to counterweights 2^c.

What I claim as my invention and desire to secure by Letters Patent is:—

1. The method of making concrete piles or columns which comprises feeding concrete in a screw-shaped spiral layer into the opening to be filled, and compacting the concrete during such deposition by a hammering action.

2. The method of making concrete piles or columns which comprises feeding concrete in a continuous screw-shaped spiral layer into the opening to be filled and compacting the concrete during such deposition by a hammering action.

3. An apparatus for making a concrete pile or column in a bore-hole or form, comprising means to deposit concrete in a screw-shaped spiral layer within the opening to be filled, a hammering means to compact the concrete during such deposition, and means to cause the depositing and hammering devices to rise by reaction of the hammering device from the concrete as the latter becomes compacted.

4. An apparatus for making concrete pile or column in a bore-hole or form, comprising a hammering feed-worm for the concrete whose diameter is approximately equal to that of the bore-hole or form, and means to rotate the said feed-worm so that it gradually forces itself out of the bore-hole by its reaction with the surface of the concrete as the latter becomes compacted thereby, substantially as described.

5. An apparatus for making a concrete pile or column, comprising a reservoir-tube, a feed-worm therein and operatively connected thereto, means to rotate the feed-worm so that it gradually forces itself and said tube away from the base of the pile or

column by its reaction with the surface of the concrete as the latter becomes compacted, and means for transmitting blows through the feed-worm to the laid concrete to compact it.

6. An apparatus for making a concrete pile or column, comprising a reservoir-tube, a feed-worm therein having a lost-motion connection therewith, means for rotating the feed-screw so that it gradually forces itself and said tube away from the base of the pile or column by its reaction with the surface of the concrete as the latter becomes compacted, and means for transmitting blows through the feed-worm to the laid concrete to compact it.

7. Apparatus for making a concrete pile or column, comprising a reservoir-tube, a hammering feed-worm therein having a lost-motion connection therewith, and means for rotating the feed-screw so that it gradually forces itself and said tube away from the base of the pile or column by its reaction with the surface of the concrete as the latter becomes compacted.

8. An apparatus comprising the combination of parts set forth in claim 5, wherein the hammering device consists of a non-rotating monkey which can slide up and down at the upper end of the tube, combined with means fixed on the rotating spindle of the feed-screw and coöperating with means fixed on the non-rotating monkey so that rotation of the spindle raises the monkey and drops it suddenly on the spindle to produce the downward hammering action thereof.

9. An apparatus comprising the combination of parts set forth in claim 6 wherein the hammering device consists of a non-rotating monkey which can slide up and down at the upper end of the tube, combined with means fixed on the rotating spindle of the feed-screw and coöperating with means fixed on the non-rotating monkey so that rotation of the spindle raises the monkey and drops it suddenly on the spindle to produce the downward hammering action thereof.

10. An apparatus for making concrete piles or columns comprising the combination of parts set forth in claim 5 wherein a hammering device for the feed-screw consists of a non-rotating monkey which can slide up and down at the upper end of the tube combined with a ratchet-toothed cam fixed on the rotating spindle of the feed-worm and a coöperating cam fixed on the non-rotating monkey so that rotation of the spindle raises the monkey and drops it suddenly onto the spindle to produce the downward hammering action thereon.

11. An apparatus for making concrete piles or columns comprising the combination of parts set forth in claim 6 wherein

a hammering device for the feed-screw consists of a non-rotating monkey which can slide up and down at the upper end of the tube combined with a ratchet-toothed cam fixed on the rotating spindle of the feed-worm and a coöperating cam fixed on the

non-rotating monkey so that rotation of the spindle raises the monkey and drops it suddenly onto the spindle to produce the downward hammering action thereon. 10

In testimony whereof I affix my signature.
ALEXANDER GEORGIEVITCH ROTINOFF.
